UNITED STATES PATENT OFFICE.

ARTHUR VON BARTH, OF NEW YORK, N. Y.

WAGE-PAYING MACHINE OR THE LIKE.

1,114,828.

Specification of Letters Patent. Patented Oct. 27, 1914.

Application filed March 10, 1911. Serial No. 613,638.

To all whom it may concern:

Be it known that I, ARTHUR VON BARTH, a citizen of the United States, residing at New York city, in the county of New York and State of New York, have invented certain new and useful Improvements in Wage-Paying Machines or the like, of which the following is a specification, reference being had therein to the accompanying drawing.

10 My invention relates to machines for handling or counting out money, and more particularly to what may be entitled pay-roll machines intended to be used in factories or elsewhere as an assistance to the counting 15 out of the money for the employees and keeping a record thereof.

Among the objects of the present invention are to provide mechanism which is easily controlled by an operator and by which 20 through automatic devices the amount of wages for each employee of a factory or other place may be counted out in both bills and coin, and a record kept thereof for the usual purposes of pay-roll records.

25 I will first describe one embodiment of my improvements and will then point out the novel features in the claims.

In the accompanying drawings forming a 30 part of this description and illustrating one manner in which my improvements may be embodied, Figure 1 is a front elevation of such a machine showing the coin mechanism at the left, the bill mechanism at the right and the controller and recorder in the center,

35 the operator being supposed to sit in front of the last named, operating it by the keys thereof and collecting the bills from his right hand and coin from his left hand according to the wages indicated by his operation of the keys. Fig. 2 is a plan view 40 of the mechanisms shown in Fig. 1. Fig. 3 is a right-hand elevation showing principally the bill mechanism and part of the control mechanism. Fig. 4 is a left-hand elevation in which all three of the mechanisms 45 are seen. Fig. 5 is a front view of certain parts, namely the motor for the bill mechanism and the clutch and connections driven by said motor, many parts of the machine being omitted to better illustrate the construction, and said view indicating diagrammatically certain of the electric connections between the bill mechanism and the control mechanism. Figs. 6 to 10 relate to 50 the bill mechanism, Fig. 6 being a partial cross-section taken on the plane 6—6 of Fig.

8 and looking toward the rear and illustrating principally the arrangement of the bill pockets. Fig. 7 is a similar view showing a modified arrangement thereof. Fig. 8 is a cross-section of parts of the bill mechanism taken on the plane 8—8 of Figs. 6 or 7. Fig. 9 shows a form of carrier which may be used instead of that shown in Fig. 8. Fig. 10 is an enlarged view, its dimensions 65 being substantially correct for ordinary sized paper money, of one of the bill pockets, together with a portion of the sprocket chain passing thereover. Figs. 11 to 16 relate to the coin mechanism. Fig. 11 is a vertical cross-section taken on the plane 11—11 of Fig. 1. Fig. 12 is a top plan view of one corner of the coin mechanism. Fig. 13 is a vertical cross-section taken on the plane 13—13 of Fig. 11. Fig. 14 is a top 70 view of the pusher or slide which pushes the coins out, while Fig. 15 is a right-hand elevation thereof, Fig. 16 is a vertical section of a part of the coin mechanism showing the drop latch which prevents the coins 75 feeding backwardly, Fig. 17 is a detail view showing the recording mechanism and the electrical connections therewith and the coin delivery mechanism; and Fig. 18 is a detail view showing said recording mechanism and the electrical connections there- 80 between and the bill delivery mechanism. 85

Similar letters of reference are employed 90 to designate corresponding parts in the several figures of the drawings.

The control and recording mechanism is preferably of a type indicated at A, Figs. 1, 2, 3 and 4, having a keyboard *z* with suitable keys thereon *a'* according to the work that the machine is to accomplish. In its 95 general principles the mechanism A may have many of the well known features of ordinary calculating machines or cash registers, and will have certain other features hereinafter to be described. The keys *a'* 100 will have the amounts of coins, bills, etc., indicated upon them, and an example of the arrangement of such marking is indicated in Fig. 2, although many other arrangements could be adopted according to the 105 needs of the particular user of the invention. This mechanism A I prefer to constitute a controlling mechanism for controlling the bill mechanism B on the one hand, and the coin mechanism M on the other 110 hand, and also to constitute a counting or calculating mechanism, preferably by print-

ing the respective amounts and their sum upon a strip of paper in a manner that is well known. The interior details of this mechanism will not be illustrated or described, as they may be made of any recognized type such as is known in the art.

As a controlling mechanism there must be connection to the coin mechanism M and the bill mechanism B, and I have chosen to represent for such connection suitable electrical circuits, whereby the depression of the proper keys in the mechanism A serves to control the mechanisms B and M. Thus each of the keys a' may effect an electrical contact in a manner that is indicated in the lower part of Fig. 1 where an extension a^2 of each of the keys a' is arranged on being depressed to contact with a member a^3 , the two forming part of an electric circuit which is indicated by the wires seen in the figure. The exact arrangement of these wires is not fully shown in Fig. 1, but will be fully understood by those skilled in the art, especially in connection with the other figures where the same is shown more fully.

It should be stated in connection with Figs. 1 and 2 that while only eleven of the keys are shown as having money values on them, there are nine further keys without money values, and these keys may be such as are frequently provided in counting and registering mechanisms for various and miscellaneous purposes of the machine, for example printing special characters, causing a total to be taken, etc.

I will now describe the bill mechanism B. The bill mechanism has a table b preferably mounted on legs as shown, and the upper part of the table b may be cut away as indicated in the dotted line at b' in Fig. 2 so as to make space to receive the different bill pockets hereinafter to be described. There are a series of six bill pockets shown marked c^1 , c^2 , c^3 , c^4 , c^5 and c^6 , each of which contains a different denomination of bills, for example fifty, twenty, ten, five and two dollars and one dollar, respectively. Each of the bill pockets is arranged so as to move upwardly and downwardly independently of the other bill pockets, and any suitable mechanism may be employed for this purpose.

The bill mechanism B has a projecting shelf in front of it with a dish-shaped recess b^2 of sufficient size to hold a few loose bills. The plan of operation of my bill mechanism is substantially as follows: Each of the bill pockets of a given denomination has a control key a' corresponding to it with connections such that when the key is depressed it causes the mechanism to operate so that the topmost bill will be abstracted from the bill pocket and then transferred out of the casing and into the recess b^2 . Before describing the circuits I will

describe the pockets more in detail and their manner of coöperation with the mechanism which transfers the bills from the pockets to the recess b^2 . The pockets according to Fig. 6 are pivoted at c^{24} so as to enable them to be swung upwardly or downwardly, they normally remaining downwardly and being lifted at such times as the operation of their respective keys occurs. When the key is pressed and the current passes an actuation will take place through a solenoid c^7 which pulls its armature c^8 , which in turn through a roller c^9 pulls down upon the arm c^{10} , which is a continuation of an arm c^{11} secured to the bill pocket c^4 , the said arms c^{10} , c^{11} affording the pivotal connection to the pivot c^{24} already referred to. When the current passes and the solenoid is energized, the arm is swung and the pocket is raised from the position seen in Fig. 6 to an elevated position which is indicated by the pocket c^5 in Fig. 8, the limit of upward movement being determined by the striking of the arm c^{10} against the solenoid. A blow is thus struck which gives a tendency in the topmost bill to move out of the pocket when it will be acted upon by the suction device hereinafter to be described. C represents a stack of bills in the pocket c^4 , and c represents the topmost bill which is the one about to be drawn from the pocket. In order to afford a tendency to feed upwardly, a weighted member c^{12} is so located in the pocket that when the latter bumps in its elevated position as described, the member c^{12} will rise under its own momentum and to a certain extent assist in the action described. A device is employed to hold the member c^{12} to its advanced position, said device comprising a pair of toothed wheels c^{13} engaging rack c^{14} formed along two opposite sides of the pocket, and there being a pair of pawls c^{15} coöperating with the toothed wheels to prevent a reverse rotation thereof and downward movement of the member c^{12} . The rack c^{14} will preferably be arranged below the inner surface of the pocket walls instead of projecting therefrom, and in this way interference with the bills is avoided.

Suction is maintained within the interior of the hollow casing B' of the bill mechanism, and the pipe B² may be considered as an exhausting means for this purpose, it obviously being capable of connection to any desired exhausting apparatus. The interior of the casing B' being exhausted, there is a continual tendency to air inflow, and this is the means that I have employed to extract the topmost bill from a pocket at each operation for the purposes of this invention. Each bill as it is lifted from its pocket by the combined action of the sudden stoppage of the pocket and of the suction or inward flow of air, is taken in charge by a trans-

ferring means and transferred to the recess b^2 . Such transferring means may comprise a belt or a carrier having a pair of sprocket chains D passing around a pair of sprocket wheels D', and a second pair of such wheels at the other end, the two chains carrying a series of cross members constituting a carrier, all contained within the casing B'. The carrier D is built up of links d^3 and 10 pivots, and I preferably extend each pivot across from one side to the other by a series of rods d. Upon each of the rods d is mounted a louvre or shutter d' which preferably is intended to turn freely about the rod 15 and consists generally of a piece of sheet metal or other material of the full length shown in Fig. 6 and of a substantial width as seen in Fig. 10 so that each shutter will extend from its own pivot to rest upon the 20 succeeding shutter, thereby substantially but not entirely closing the space between the rods against the flow of air. Fig. 8 shows the shutters d' resting thus one upon the other except at a point directly above the 25 pocket c⁵ where the shutters are opened in a manner and for a reason which will be described.

It is desired to concentrate the action of the inflowing air or of the suction to the bill 30 pocket which is in operation, and it is for this reason that I have provided the shutters referred to so that the inflow of air will be generally prevented. Such inflow, however, and the full action of the suction will be permitted 35 above the bill pocket which is in operation, and this may be effected by the following means. Referring to Figs. 6, 8 and 10, each of the swinging pockets c⁴ has a series of fingers c¹⁶, they being held substantially vertical by means of springs c¹⁷ in a yielding manner so that there will be no breakage. On the elevation of the bill pocket the fingers c¹⁶ will rise between the rods d of the 40 sprocket chain and will contact and force 45 open the shutters d' directly above the pocket, this action being clearly seen in Fig. 8 where three shutter spaces are open exposing the topmost bill directly to the pneumatic action. Upon rising to the position 50 shown in Fig. 8, the bill pocket immediately drops to its normal position, but the combined actions described cause the topmost bill to be held against the carrier D, it being thus drawn from the pocket; and there will 55 always be sufficient leakage of air to cause the bill to sufficiently adhere to the carrier so as to be carried along with it in the direction of the arrow in Fig. 8 until the pointed edge B² of the casing B' engages the bill 60 and diverts it into the recess b² of easy access to the operator. At each end of the shutter d' is seen a nose projection c¹⁸ whose purpose is to coöperate with the fingers c¹⁶ and divert them one way or the other from 65 the vertical, and thus prevent breakage.

This action will be clearly understood from Fig. 10.

The construction and operation as regards Fig. 7 are substantially on the same principles as with Fig. 6, the difference being that in the case of Fig. 7 the bill pocket does not swing upwardly and downwardly but maintains the bills in horizontal position while lifting is being done in this case with a pair of solenoids c¹⁹ and c²⁰. In either form of device seen in both Figs. 6 and 7, a strip c²¹ may be employed secured at each side of the lower walls of the casing B' to shut off to some extent possible leakage of air at those points. Contrivances c²² in the form of strips of extremely light celluloid or other material may be employed along the upper side edges of the pockets to give some resistance preventing the bills from freely passing out at the top and also preventing two bills from being lifted by accident at the same time, while permitting the top bill to be drawn out under the actions already referred to. An important function of the strips c²² is to prevent air flow edgewise beneath the uppermost bill, for this if it occurred would tend to separate and abstract from the pocket more than the top bill. In order, however, to allow air to be admitted between the top and the second bills, I have provided cut away spaces at c²³ along the top side edges of the pocket beneath the strips c²², and air may also enter at the ends which are open as seen in Fig. 3.

The shutters d' may be dispensed with in some cases and with them the fingers c¹⁶, and in such a case a sprocket device or carrier of the construction seen in Fig. 9 may for example be employed, in which the air passages between the members d² are comparatively small and yet sufficiently large to permit the full action of the suction in extracting the top bill from the pocket. Fig. 9 shows the links d³ of the sprocket chain, and such form of links is also seen in the upper part of Fig. 8, they being omitted in the lower part to more clearly show the construction of the shutters. It will be clear that the motion of the sprocket wheels and sprocket chain while usually continuous must be interrupted and the chain held stationary for short intervals, namely during the extraction of each bill from a pocket. Thus in Fig. 8 the pocket c⁵ is seen to have risen for the purpose of having a bill extracted therefrom and the fingers c¹⁶ are actually engaged in the sprocket spaces. To effect stoppage at such times and permit it to thereafter resume, the following mechanism may be employed: E, Figs. 1, 3, 4 and 5, represents an electric motor driven by any source of electricity or otherwise, and in its turn driving a shaft e continuously. Said shaft is journaled at e' and at one end is provided with a clutch member e² which is 130

keyed to the shaft so as to slide back and forth thereon, and which cooperates with a second clutch member e^2 to which is connected a pulley e^4 that normally drives a belt e^5 , which in turn drives a pulley e^6 mounted on the shaft e^7 of the rear sprocket wheel. The clutch e^2, e^3 is controlled by a yoke arm e^8 pivoted to a fixed part of the machine at e^9 and having connected to it at e^{10} an armature e^{11} which is operated by a solenoid e^{12} . When the solenoid is energized, it attracts its armature and moves the yoke arm e^8 from left to right so as to disengage the clutch as seen in Fig. 5, there being a spring e^{13} of less strength than the solenoid to restore the clutch to operative position so that the rotation of the sprockets will resume when the current of electricity is cut off. The electric circuit containing the solenoid e^{12} is shown as broken and having two extensions at e^{14} which extend to the terminals of the solenoid e^7 already referred to, for purposes that will appear in the following statement of the operation of the parts.

When the operator desires to pay a workman the wages, for example, of \$18.00, he will press in succession the keys marked \$10.00, \$5.00, \$2.00, \$1.00, and upon each such key operation substantially the same operation will take place with the corresponding pockets containing bills of those denominations. Taking one of the pockets for an example, the operation will be as follows: As already explained the pressure of the key closes the circuit by the contacting of the points a^2 and a^3 . This circuit includes any source of electricity such as is conventionally illustrated at E' , and the circuit also includes the solenoids e^{12} and e^7 which are preferred to be operated simultaneously. The energizing of the solenoid e^{12} causes the opening of the clutch e^2, e^3 , and the slow moving traveler or sprocket comes to rest at once. While this is occurring the energizing of the strong solenoid e^7 causes a sudden downward throw of its armature and upward throw of the bill pocket e^4 , Fig. 6. The bill pocket on reaching its highest point of elevation immediately bounces back to its lower position, but at the instant when it is highest the combined bumping action described and that of the exhausted air cause the topmost bill to be extracted, the bill thereupon being sucked inward so as to be maintained in contact against the lower side of the traveler. The operator on depressing a key releases it as soon as he may desire and this release effects the reengagement of the clutch e^2, e^3 , and thus re-starts the rotation of the traveler, which thereupon conveys the bill from its position above its pocket, until as described it is delivered into the recess b^2 . The

pressure of the four keys in succession delivers into the recess b^2 bills of the denominations of \$10.00, \$5.00, \$2.00 and \$1.00, thus making up the amount of the wage which is paid over to the workman. At the same time, as already explained, certain registering or counting or printing operations take place within the controller A so that a complete record is kept of the financial transactions carried on by the apparatus.

I will now describe the coin mechanism M. As illustrated this comprises an open top casing M' within which are coins of different denominations and in front of which at the lower portion is an extension M^2 having a recess m for the coins fed out. The casing is divided into a series of compartments by means of strips m' , each compartment adapted to hold coins of a given denomination, for example 1¢, 5¢, 10¢, 25¢, 50¢. These compartments may be considered as money containers just as the pockets c^1, c^2 , etc., of the bill mechanism constitute money containers, and their purpose is analogous in that in each case the depression of the proper key of the controller A feeds outwardly a piece of money of the corresponding denomination. With the two mechanisms a given wage may be fed out of an amount requiring both bills and coins to make it up. The coin compartments within the casing M' may each be longer than its width so as to contain a number of columns of coins of the same denomination, and these may conveniently be separated from each other by divisions as seen in Fig. 12. By this arrangement the coin mechanism is enabled to contain a very large number of coins, and the feeding out mechanism which will be described, is adapted to feed out successively from each of the different columns without the need of any special attention by the operator or any re-adjustment of the mechanism after one column has been exhausted. Each of the compartments has a coin exit in front, for example the first or nickel compartment has a coin exit at m^2 , such exit consisting in a horizontal slit of sufficient depth to permit one coin but not two to pass outwardly; and each of the compartments will have such a slit, they being of varying depths according to the coins. Each of the compartments may have a flat bottom surface, as clearly indicated in Fig. 11. The divisions m^3 contained in the compartments are each caused to stand slightly above the flat bottom so as to permit coins to pass forwardly under the divisions in a manner that will be explained. The divisions may be secured in place either by a sliding connection as seen at m^4 in Figs. 12 and 13, or a pivotal connection as seen at m^5 . In the latter case the divisions may be swung to an inclined position and

in both cases the feature of movability is an assistance in putting coins into and taking them out of the compartments.

The means for feeding coins out is shown as a pusher or slide N having a stem n and forked beyond the stem in two branches n' and n'' , said branches passing forward in parallelism to whatever extent may be necessary to correspond with the number of columns of coins in each compartment. The pusher seen in Figs. 14 and 15 is of a size for three columns of coins, and its application is more clearly seen in Fig. 12. In action the pusher rests upon the flat bottom of its compartment and slides forwardly and backwardly thereon in the act of pushing coins out of the compartment. The walls m' between the compartments and the side walls M' of the casing are grooved or cut away at n^3 and n^4 to admit the pusher, and in fact as seen in Fig. 13 I prefer that the wall m' should not extend to the bottom of the casing, but be suspended slightly thereabove so as to admit space for the side rails or branches n' n'' of the several pushers. The means which actually accomplishes the pushing out of the coins consists in a plurality of projections n^6 formed preferably in pairs on opposite sides of the pusher, and of such construction that on each forward movement of the pusher the projections will engage the lowermost coins and shove them forward so that in the full operation of the machine each complete forward movement of the pusher forces a single coin out from the compartment into the recess m in front. In order that the pusher may be returned to its backward position notwithstanding the presence of the projections n^6 , the latter are made in the form of wedges with inclined rear surfaces n^7 so that they may ride easily under the coins. In conjunction with the wedge projections n^6 I prefer to employ also a means to prevent coins being fed backwardly and this may conveniently comprise drop latches n^8 , each of which is shown mounted centrally in one of the division walls m^3 , the latter having an interior passage from top to bottom to permit the free movement of the latch. The lower end of each latch is inclined as seen at n^9 , Figs. 13 and 16.

In the operation of a pusher of the construction described, referring to Fig. 11, coins will be fed on each reciprocation of the pusher and will be drawn from the rearmost column O of the coins in such compartment. To describe the action in detail it is as follows; Fig. 12 shows the pusher N in its backward position. The several projections n^6 are behind the three respective bottom coins of the three columns. The several latches n^8 are inclined at their lower ends so as to permit forward movement but to prevent backward movements of the coins.

With this condition of affairs, the pusher is shoved forwardly the distance approximately the diameter of one coin. The three bottom coins are thereby each moved forwardly to the extent of one diameter, and the forward coin o passes out from the front slit into the recess m of easy access to the operator. At the same time the other two coins are each moved forwardly taking their place beneath the next succeeding columns, and at the end of the front stroke of the pusher the rear column O will drop to the extent of the thickness of a single coin and a new coin will thereby engage the pusher in the space n^{10} thereof. On the backward movement of the pusher the several pairs of wedge projections n^6 will pass easily under the several columns of coins, and the pusher will be returned to its normal position or that seen in Fig. 12, while the coins will be prevented from moving backwardly with the pusher by means of the latches n^8 standing in their way. The rearmost wall does not require a drop latch with inclined bottom face, but instead is provided with a fixed lug or projection n^{11} which stands permanently in position to prevent any coins passing backwardly out of the compartment.

A convenient means to actuate the pusher N is as follows: A solenoid P may be employed having an armature p acting upon one arm p' of a bell crank lever which is pivoted at p^2 and has a second arm p^3 forked at p^4 . The rear end of the pusher is formed as seen in Figs. 14 and 15 with a pair of supporting extensions p^5 for a pin p^6 , and the parts are so arranged that the fork p^4 straddles the pin p^6 , in consequence of which the inward and outward movement of the armature p effects a forward and backward movement of the pusher, and the extent of such movement will be in accordance with the size of the coin handled in the compartment, to which the pusher applies. A spring p^7 may be employed and conveniently located about the armature p for the purpose of forcing the bell crank lever back to its normal position, thereby returning the pusher to its rearward position. The solenoid will be sufficiently powerful to overcome the force of the spring p and the friction and other resistance of the coins in being moved forwardly. To energize the solenoid any source of electricity, conventionally illustrated at E', may be employed, and a conductor p^8 may be employed to complete a circuit through the solenoid, the source of current and the control device. It has already been explained that in the control mechanism there is an electrical contact device a^2 , a^3 consisting of two contacts which are adapted to be brought together by the depression of the proper key. For example if the key marked 5¢ is depressed, it will effect a contact between the contacts 130

a^2 , a^3 , and complete the circuit so as to energize the solenoid P corresponding to the compartment which contains five-cent pieces. In this way the depression of the key not only records and calculates as before exemplified, but effects the feeding out of a five-cent piece from the coin compartment into the recess m . A bracket or support p^{10} Fig. 1 may be employed to support the solenoid P in convenient relation to the control mechanism A , and an extension p^{11} of the table of the control mechanism may constitute the support for the coin mechanism.

The recording mechanism includes there-
15 in a series of type bars p^{12} actuated through
the heel p^{12} , each said type bars being pro-
vided with a type head p^{14} adapted to record
through a type ribbon p^{15} . The type bars
are actuated through the compressible mem-
bers p^{16} controlled by the keys a' and an in-
terposed lever member p^{17} acting upon the
heel p^{12} of the type bar. By this means the
recording mechanism is actuated by the de-
pression of any key a' , the depression of
25 each key also closing a circuit through the
electrical contacts a^2 , a^3 , to a bill or coin
container, the denomination of the contents
of which corresponds with the number in-
dicated by any key.

30 What I claim and desire to secure by Letters Patent is:

1. A machine of the kind described em-
bodying therein a series of containers each
adapted to receive a pile of bills, and selec-
35 tively operative means common to all said
containers whereby the bills may be removed
one at a time from any container and a con-
veying mechanism imparting movement to
said means whereby each bill as removed
40 from a container will be conveyed there-
from and delivered to the operator.

2. A machine of the kind described em-
bodying therein a series of containers each
adapted to receive a pile of bills, and selec-
55 tively operative pneumatic means common
to all said containers whereby the bills may
be removed one at a time from any con-
tainer, and a delivery mechanism acting in
conjunction with said pneumatic means
60 whereby each bill as removed from its con-
tainer is delivered to the operator.

3. A machine of the kind described, em-
bodying therein a series of containers, each
adapted to receive a pile of bills, pneumatic
means whereby one bill at a time may be re-
55 moved from its container, selectively opera-
tive means common to all said containers
whereby said means may be rendered opera-
tive as to any container, and a delivery
60 mechanism operative in conjunction with
said pneumatic means whereby each bill re-
moved from its container is delivered to the
operator.

4. A machine of the kind described em-
bodying therein a series of independently

movable containers each adapted to receive
a pile of bills, means adapted to remove one
bill at a time from any container, a delivery
mechanism acting in conjunction with said
means whereby each bill removed is de-
70 livered to the operator, and selectively op-
erative means whereby any container may
be moved into the operative relation to said
first named means.

5. A machine of the kind described em-
bodying therein a series of independently
movable containers each adapted to receive
a pile of bills, pneumatic means adapted to
remove one bill at a time from any container,
75 a delivery mechanism acting in conjunction
with said means whereby each bill removed
is delivered to the operator, and selectively
operative means whereby any container may
be moved into the operative relation to said
80 first named means.

6. A machine of the kind described, em-
bodying therein a series of independently
movable containers each adapted to receive
a pile of bills, pneumatic means common to
all said containers, adapted to remove one
90 bill at a time from any container, a delivery
mechanism acting in conjunction with said
means whereby each bill removed is de-
livered to the operator, and selectively op-
erative means whereby any container may
95 be moved into the operative relation to said
first named means.

7. In a machine of the kind described, the
combination of a series of independently
movable bill containers, means for selec-
tively moving any container, an endless car-
rier inclosed in a casing and pneumatic
means acting through said casing and car-
rier for withdrawing a bill from a moved
105 container.

8. A machine of the kind described em-
bodying therein a series of containers each
adapted to receive a pile of bills, pneumatic
means common to all said containers where-
110 by one bill at a time may be drawn from
a container, comprising a casing, means
evacuating air from said casing, a traveler
having openings therethrough, and means
actuating said traveler whereby each bill re-
115 moved is delivered to the operator, and se-
lectively operative means whereby said
pneumatic means may be made operative as
to any container.

9. In a machine of the kind described, the
combination of a series of upwardly and
downwardly movable bill containers, means
for selectively withdrawing the topmost
bills therefrom, and feeding means for each
120 container comprising a feed member, as c^2 ,
adapted to be moved upwardly by momen-
tum, and a device for preventing its down-
ward movement.

10. In a machine of the kind described,
the combination of a series of bill containers,
125 a carrier having openable and closable shut-

ters, pneumatic means for maintaining suction on the side of the carrier opposite the containers, and means for selectively opening shutters for withdrawing bills from containers.

11. In a machine of the kind described, the combination of a series of movable bill containers, a carrier having openable and closable shutters, pneumatic means for maintaining suction on the side of the carrier opposite the containers, and fingers movable with each container for causing shutters to open for making said pneumatic means operative to withdraw a bill from said container.

12. In a machine of the kind described, the combination of a container for bills, means acting on the face of the topmost bill for withdrawing it, and a yielding air-tight device projecting over the edges of the bills.

13. In a machine of the kind described, the combination of a container for bills, pneumatic means acting on the face of the topmost bill for withdrawing it, and a yielding air-tight device projecting over the edges of the bills for preventing upward air flow from acting at the bill edges.

14. In a machine of the kind described, the combination of a container for bills, pneumatic means acting on the face of the topmost bill for withdrawing it, and a yield-

ing air-tight device projecting over the edges of the bills for preventing upward air flow from acting at the bill edges; said container having a series of air openings beneath said yielding device.

15. A machine of the kind described embodying therein a series of movable containers, each adapted to receive a pile of bills, means adapted to remove one bill at a time from a container, a continuously moving carrier adapted to deliver each bill removed to the operator, selectively operative means for moving each container into the operative relation to said first named means, and means controlled by said last named means whereby said carrier is stopped while said container is in the operative relation to the means removing a bill therefrom.

16. In combination with a controller, an electric circuit, a solenoid therein, a movable bill container, connections whereby the solenoid moves the container, and means for withdrawing a bill from such container when so moved.

In testimony whereof I have affixed my signature in presence of two witnesses.
